(57) **CLAIM**

The ornamental design for a lap desk with foldable arm and magnetic panel for mobile phone support, as shown and described.

DESCRIPTION

FIG. 1 is a top, front right perspective view of the lap desk with foldable arm and magnetic panel for mobile phone support showing our design in a first state with the foldable arm folded;

FIG. 2 is a lower, front left perspective view thereof;

FIG. 3 is a top view thereof;

FIG. 4 is a bottom view thereof;

FIG. 5 is a left view thereof;

FIG. 6 is a right view thereof;

FIG. 7 is a rear view thereof;

FIG. 8 is a front view thereof;

FIG. 9 is a top, front right perspective view of the lap desk with foldable arm and magnetic panel for mobile phone support showing our design in a second state with the foldable arm raised and the magnetic panel in a first position;

FIG. 10 is a lower, front left perspective view thereof;

FIG. 11 is a top view thereof;

FIG. 12 is a bottom view thereof;

FIG. 13 is a left view thereof;

FIG. 14 is a right view thereof;

FIG. 15 is a rear view thereof;

FIG. 16 is a front view thereof;

FIG. 17 is a top, front right perspective view of the lap desk with foldable arm and magnetic panel for mobile phone support showing our design in a third state with the foldable arm raised and the magnetic panel in a second position;

FIG. 18 is a lower, front left perspective view thereof;

FIG. 19 is a top view thereof;

FIG. 20 is a bottom view thereof;

FIG. 21 is a left view thereof;

FIG. 22 is a right view thereof;

FIG. 23 is a rear view thereof;

(Continued)

FIG. 24 is a front view thereof;
 FIG. 25 is a top, front right perspective view of the lap desk with foldable arm and magnetic panel for mobile phone support showing our design in a fourth state with the foldable arm raised and the magnetic panel in a third position;
 FIG. 26 is a lower, front left perspective view thereof;
 FIG. 27 is a top view thereof;
 FIG. 28 is a bottom view thereof;
 FIG. 29 is a left view thereof;
 FIG. 30 is a right view thereof;
 FIG. 31 is a rear view thereof; and,
 FIG. 32 is a front view thereof.
